CLAIM

I claim the ornamental design for a battery, as shown and described.

DESCRIPTION

FIG. 1 is a left side view of a battery embodying the invention.

FIG. 2 is a right side view of a battery embodying the invention; and,

FIG. 3 is a top view of the battery embodying the invention. The design application is directed to a portion of a battery as illustrated in the drawings. Other features of the drawings, specifically, the housing of the battery and locking mechanism, are not part of the design sought to be patented, and have accordingly be shown in broken lines.
